UNITED STATES PATENT OFFICE.

C. CALVERT EGERTON, OF BALTIMORE, ASSIGNOR OF TWO-THIRDS TO BENJ. G. HARRIS, OF SAME PLACE, AND WILLIAM CANBY, OF BALTIMORE COUNTY, MARYLAND.

STANDARD FOR CARRIAGE-TOPS.

SPECIFICATION forming part of Letters Patent No. 239,944, dated April 12, 1881.

Application filed February 3, 1881. (No model.)

To all whom it may concern:

Be it known that I, C. CALVERT EGERTON, of Baltimore city, State of Maryland, have invented certain new and useful Improvements 5 in Standards for Carriage-Tops; and I do hereby declare the same to be fully, clearly, and exactly described as follows, reference being had to the accompanying drawings, in which—

Figures 1 and 2 are side elevations, respectively, of the upper and lower ends of the standard. Fig. 3 is a central sectional view of the part shown in Fig. 1, and Fig. 4 a similar view of the part shown in Fig. 2.

My invention has reference to standards for 15 sustaining the tops or canopies of children's carriages; and it has for its object to provide a standard adapted to tilt forward and back and to sustain the canopy at any desired angle with reference to the standard, which end 20 is attained by articulating the standard twice between its points of attachment to the canopy or top and to the body and providing each joint with an independent locking device.

Generically my invention consists in a 25 standard embodying such construction; and specifically it consists in certain features of construction of the locking device for securing the upper and lower joints, the latter being an improvement upon that for which Letters Patent 30 were granted me August 10, 1880, and numbered 230,930, as hereinafter set forth.

Referring now to the accompanying drawings, A is the upper extremity of the standard, having eyes *a* for the screws which secure it to the top, and having an arc, B, provided with slots *b*. The upper ends of the slots are flaring or bell-shaped, as shown, to facilitate the entrance of the securing-lug. The part A has on the inside a pin, *b'*, provided with a downwardly-projecting lip, *b''*, which pin rests in a slot in the upper end of the central part, D, of the standard. On the part D is formed a thimble, C, in which plays a pin, *f*, that is normally depressed by a spring, *e*, the extent of 40 its downward motion being determined by a transverse pin or rivet, *f'*. A lug, *e'*, is formed on the pin *f* and engages with the slots *b* of the arc B. A suitable head or button, E, is attached to the lower end of the pin, to facilitate

its being lifted against the resistance of the 50 spring. Lugs C are formed on the part D, between which the pin *f* or button E plays, and which serve to guide the pin as it is raised or lowered.

In order to alter the angle of inclination of 55 the top to the main part of the standard, the operator simply raises the button E and cant the top as desired. On releasing the button the pin *f* is thrust downward by means of the spring, and the lug *e'* is made to enter any 60 desired one of the slots *b*, locking the top in place. The peculiar allocation of parts is most convenient for effecting this adjustment, as, the hands of the operator being laid on the top of the canopy at the edge, just over the joint, 65 the button is in convenient reach of the fingers. The part D terminates below in a wheel, *d*, having a number of projections, *d''*, located, by preference, 45° apart, and having also trunnions *d'*, which rest in curved sockets *g* in the 70 parts G and H, exactly in the manner described in my patent above referred to.

A mirror, D', or, rather, two mirrors, placed back to back, are mounted in the part D, as shown. The inside mirrors are about the level 75 of the head of the child seated in the carriage, and serve to amuse it as it perceives its reflection therein. The mirrors may be pendent in the standard instead of rigidly affixed therein, if desired.

H is the side plate, which is held to the lower part, G, of the standard by means of rivets *g'* *m*, and has at its base a thimble, *h*, which encloses a spring, *J*. I is a rod, which is normally thrust upward by means of that spring, 85 and carries at its upper end a transverse head, *i'*, of a length to fill the space between one of the projections *d''* and the next but one, and having an indentation, *i''*, to receive the intermediate projection, and indentations *i'''* at 90 either side of the central one at a distance apart equal to that which separates the projections.

The pin is slotted, as shown at *i*, and the rivet *g'* passes through the slot, and serves to 95 guide the pin.

A plate, *g''*, is formed on the part G, and constitutes the base of the thimble.

At the base are eyes *l* for the screws which attach the standard to the carriage-body.

To tilt the central portion of the standard with reference to the carriage-body, it is only necessary to push the canopy in the desired direction, when the pin *I* is depressed by the projections of the wheel *d*.

It will be seen that between the practical extremes of adjustment—viz., when the standard is horizontal either to the front or rear—there are seven other possible adjustments, making nine in all, since the standard is secured with all desired rigidity when a projection, *d''*, is in the central depression, *i''*, or when two projections are in the indentations *i'''*. In a word, the standard may be secured at points twenty-two and one-half degrees apart on either side of the vertical down to the horizontal, a range and nicety of adjustment answering every requisite. The indentations *i'''* are not absolutely necessary, as the points *d''*, when equidistant from the central indentation *i''*, furnish a polygon of support whose longer sides equal those of the inscribed octagon of the wheel, and furnish abundant stability precisely in the same degree, it may be remarked, attending the construction shown in my patent hereinbefore referred to.

The parts *A* and *D* may most readily be detached to renew the springs *e* or *J* should they break or become weak.

On removing the pin *f'* the pin *f* will fall out of the thimble, and the arc *B*, being sprung clear of the lugs *c*, the canopy may be lifted off.

The parts *D* may be separated from the base-piece by simply lowering them to a horizontal position, depressing the trunnions to clear the lower edge of the curved lips *g*, and drawing the parts *D* laterally from between the plate *H* and base-piece *G*.

It will be seen that the movement of the canopy with reference to the standard is in-

dependent of that of the latter with reference to the carriage-body, so that the canopy may be adjusted to a horizontal position at either 45 side of the perpendicular.

What I claim is—

1. A carriage-standard having a top piece pivoted thereto and adapted for attachment to the top or canopy, and provided with a slotted 50 arc and a vertically-sliding button or lug for locking the said arc, as set forth.

2. A carriage-standard having an indentation or slot in its upper end, in which rests the pivot of the part which sustains the canopy, 55 whereby the same is rendered readily removable, as set forth.

3. In combination with the standard, the part *A*, pivoted thereon and having the slotted 60 arc *B*, the button *E*, lug *c'*, and spring *e*, as set forth.

4. In combination with the standard *D*, having the thimble *C*, pin *f'*, and spring *e*, the part *A* and arc *B* having flaring slots *b*, as set forth.

5. In combination with the part *A*, having 65 slotted arc, the standard *D*, provided with lugs *C*, for guiding the locking device, and the arc, as set forth.

6. The standard *D*, having the wheel *d*, provided with projections, as set forth, in combination with the bar *I*, having transverse head *i'*, as set forth. 70

7. In combination with the standard having wheel provided with projections *d''*, the bar *I*, having head *i''*, indented for engagement with 75 the projection, as set forth.

8. In combination with the base-piece, plate *H*, and standard having wheel *d*, the slotted bar *I*, having transverse head, and the spring *J*, as set forth.

C. CALVERT EGERTON.
